UNITED STATES PATENT OFFICE.

JOHN H. HOLLISON AND CHARLES H. MILLER, OF CHICAGO, ILLINOIS.

DESIGN FOR A DENTAL DIE DEVICE.

57,044.

Specification for Design.

Patented Feb. 1, 1921.

Application filed January 27, 1919. Serial No. 273,489. Term of patent 14 years.

To all whom it may concern:

Be it known that we, JOHN H. HOLLISON and CHARLES H. MILLER, citizens of the United States, residing at Chicago, in the county of Cook and State of Illinois, have invented a new, original, and ornamental Design for a Dental Die Device, of which the following is a specification, reference being had to the accompanying drawing, forming part thereof.

Figures 1 and 2 are perspective views

taken from respectively opposite sides of the dental die device.

We claim:

The ornamental design for a dental die device substantially as shown.

JOHN H. HOLLISON.
CHARLES H. MILLER.
